UNITED STATES PATENT OFFICE.

WILLIAM HARROP AND PATRICK F. FARRELL, OF TAUNTON, MASSACHUSETTS.

SLIVER LAP-MACHINE.

No. 919,008.

Specification of Letters Patent.

Patented April 20, 1909.

Application filed August 17, 1908. Serial No. 448,961.

To all whom it may concern:

Be it known that we, WILLIAM HARROP and PATRICK F. FARRELL, citizens of the United States, residing at Taunton, in the county of Bristol and State of Massachusetts, have invented certain new and useful Improvements in Sliver Lap-Machines, of which the following is a specification, reference being had to the accompanying drawings.

10 This invention relates to improvements in sliver lap machines and more particularly to guide devices for use on such machines.

The object of the invention is to provide improved means for guiding the slivers as 15 they enter the drawing rolls and the calender rolls and thereby make the lap more even and compact so that it will be without breaks and will run better and consequently increase the production of the combing ma- 20 chines.

A further object of the invention is to provide guide devices of this character which will be simple and inexpensive in construction, which may be quickly and easily ad- 25 justed to accommodate any number of slivers from twelve to twenty and which will dispense with the necessity of using ribbon lap machines and also require less attention of the operator and thereby decrease the cost 30 of production, lessen waste and insure better work.

With the above and other objects in view, the invention consists of the novel features of construction and the combination and ar- 35 rangement of parts hereinafter fully de- 30 scribed and claimed, and illustrated in the accompanying drawings, in which—

Figure 1 is a vertical section through a portion of a sliver lap machine illustrating the 40 application of the improved guides; Fig. 2 is a detail section, on an enlarged scale, of the parts shown in Fig. 1; Fig. 3 is an enlarged perspective view showing the improved guides upon the portion of the sliver lap ma- 45 chine on which they are mounted; Fig. 4 is a detail perspective of the main or sliver guide plate and its adjustable supporting brackets; Fig. 5 is a detail vertical section through the parts shown in Fig. 4; Fig. 6 is a detail perspective of one of the selvage guides; and Fig. 7 is a detail section through 50 the same showing the manner in which it is supported and adjusted.

In the drawings 1 denotes a portion of the 55 frame of an ordinary sliver lap machine, 2 the apertured sliver guide plate, 3 the spoons,

4 the drawing rolls, 5 the calender rolls, 6 the winding spool, 7 the fluted calender rolls, and 8 the guide plate between the calender rolls 5 and 7.

60 9 denotes the slivers and 10 the sliver cans.

All of the above parts are old and well known and form no part of the present in- vention.

11 denotes the improved main guide for 65 the slivers. This guide is in the form of a vertically disposed plate arranged immedi- ately in advance of the drawing rolls and ad- justable in both vertical and horizontal planes. The slivers pass over the upper edge 70 12 of this plate, which edge is cut away on an arc, as clearly shown in Fig. 4, so that the different slivers will be caused to enter the drawing rolls in a perfectly uniform position. The guide plate is supported and adjusted by 75 means of two brackets 13 each of which has a base portion 14 arranged upon a horizontal plate on the frame 1 and a vertically project- 80 ing standard 15 to which the guide plate is secured. The standards 15 of the two brack- 85 ets are formed with vertical slots 16 to re- ceive clamping screws 17 which enter threaded openings or sockets 18 in the guide plate adjacent to its ends. The base plates 14 of the two brackets are formed with longitudi- 90 nal slots 19 to receive clamping screws 20 which enter threaded openings in the frame 1. The slots 19 and screws 20 permit the brackets and, consequently, the sliver guide plate 11 to be adjusted in a horizontal plane 95 or transversely of the machine and the slots 16 and screws 17 permit said plate 11 to be adjusted in a vertical plane. It will be seen therefore that these adjustments of the sliver 100 guide plate permit it to receive any number of slivers from twelve to twenty and that the adjustment may be quickly and easily ef- fected.

21 denotes the improved selvage guides which are arranged immediately in front of 100 the calender rolls 5 and cause the lap to be built up firmer and, consequently, prevent “the splitting and licking up” of the lap. These guides are similar, one being on each side of the sheet of sliver and each consist- 105 ing of a semi-cone-shaped tube 22 fixed on one end of a supporting and adjusting plate 23. The latter engages the bearing of the calender rolls 5 or any other portion of the frame 1 and is formed with a longitudinal 110 slot 24 to receive a clamping screw 25 which enters a threaded socket 26 in said bearing,

as shown more clearly in Fig. 7. The provision of the slot 24 and the screw 25 permit of an extensive horizontal adjustment of the selvage guide and also of a limited vertical or angular adjustment. Said horizontal adjustment of the two selvage guides permits them to be adjusted to accommodate any number of slivers from twelve to twenty.

We have found in practice that when our improved guides are used on sliver lap machines the work produced is much more even than that produced on the ordinary machines and that there is consequently less waste in the combing machines. The invention not only causes better work to be produced by the machine and lessens waste, but also effects a saving in labor since the lap will unwind in a perfectly smooth sheet without any attention from the operator and thus enables one operator to attend to a larger number of combing machines.

Having thus described the invention what is claimed is:

1. In a sliver lap machine, the combination with the frame, the spoons, and the drawing rolls, of a stationary sliver guide plate arranged between the spoons and drawing rolls and disposed vertically, said guide plate being located close to and in advance of the drawing rolls and having its upper edge formed with a longitudinal curvature having its lowest point at its center, whereby the slivers will be caused to enter the drawing rolls in a uniform position to render the lap even and regular and means whereby said guide plate may be adjusted in both vertical and horizontal planes.

2. In a sliver lap machine, the combination with the frame, the spoons, and the drawing rolls, of a stationary sliver guide plate arranged between the spoons and drawing rolls and disposed vertically, said guide plate being located close to and in advance of the drawing rolls and having its

upper edge formed with a longitudinal curvature having its lowest point at its center, whereby the slivers will be caused to enter the drawing rolls in a uniform position to render the lap even and regular, right angular supporting and adjusting brackets, one for each end of the guide plates and each consisting of a slotted base plate and a slotted standard, and fastenings passed through the slots in the standards and into the guide plate and through the slots in the base plate and into the plate, whereby the guide plate may be adjusted in both vertical and horizontal planes.

3. In a sliver lap machine, the combination with the frame, the drawing rolls and the calender rolls, of a pair of selvage guides, each having a semi-cone-shaped guide portion to engage one edge of the sheet of sliver and a longitudinally slotted attaching plate projecting from the semi-cone-shaped guide portion and pivoting and adjusting screws passed through the slotted attaching plates and into the frame, whereby the selvage guides may be adjusted horizontally toward and from each other and also angularly in a vertical plane.

4. In a sliver lap machine, the combination with the frame, the drawing rolls and the calender rolls, of a sliver guide plate disposed vertically in front of the drawing rolls and having a curved upper edge, means for adjusting said guide plate in both vertical and horizontal planes, and selvage guides horizontally adjustable upon the frame and having semi-cone-shaped guide portions to engage the edges of the sheet of sliver.

In testimony whereof we hereunto affix our signatures in the presence of two witnesses.

WILLIAM HARROP.
PATRICK F. FARRELL.
